UNITED STATES PATENT OFFICE

CHARLES C. SUNDERLAND, OF NEW BRUNSWICK, NEW JERSEY, ASSIGNOR TO JOHN A. ROEBLING'S SONS COMPANY, OF TRENTON, NEW JERSEY, A CORPORATION OF NEW JERSEY

METHOD AND APPARATUS FOR SPINNING BRIDGE CABLES

Application filed February 25, 1931. Serial No. 518,111.

This invention relates to spinning cables, and is especially adapted for spinning suspension bridge wire cables of the parallel wire type, in which the wires are laid up parallel into cables or to form strands and these strands bunched into cables, the object of the invention being to provide an improved method and apparatus for this purpose, in which a higher speed of cable construction shall be secured.

In spinning parallel wire cables on large suspension bridges, the method usually employed heretofore is as follows: For each main cable, there is installed a continuous tramway or traction rope running between the bridge abutments, and carrying two spinning wheels, which move in opposite directions across the span and return, one spinning wheel being at one end of the cable when the other wheel is at the other end. Wire is laid by this arrangement in four individual strands by one spinning wheel carrying a wire for one strand over the span and on its return trip carrying a wire for a second strand, while the other spinning wheel carries a wire for a third strand across the span and on the return trip carries a wire for a fourth strand. In the use of this method, it is obvious that the wire reels and unreeling mechanisms for two strands are not in use during the trip across the span for the other two strands, so that, although four wire reels and unreeling mechanisms are required for the four strands of any one main cable, there are only two reels and unreeling mechanisms in operation at one time, involving a waste in equipment operation. Further, there are required a large number of men distributed throughout the length of the span for positioning and adjusting the wire in the strands and the strands in the cables, there being one complete gang required for each pair of strands, and there is a considerable period of time, amounting to about half time, in a long span, when these gangs of men are doing nothing but simply waiting for the trip of the spinning wheels to be completed.

The present invention decreases largely the time required for spinning cables and reduces the idle period of the men and unreeling

mechanism without increasing materially the equipment or labor cost, by using tramways, each of which runs only about one half of the span, these tramways running from opposite ends of the cables so as to meet at an intermediate point of the cable length. At this intermediate point, the wires are transferred from one spinning wheel to the other for the return trip of the latter, so that each wire is laid to an intermediate point of the cable by a spinning wheel on one tramway and then carried through the remaining length of the cable by the other spinning wheel on its return trip. Four strands may thus be spun with two tramways each carrying two spinning wheels moving in opposite directions.

For a full understanding of the invention, a detailed description of an apparatus for carrying out the invention in its preferred form and its method of operation, in connection with laying a bridge cable, will now be given in connection with the accompanying drawings, forming a part of this specification, and the features forming the invention then particularly pointed out in the claims.

In the drawings:

Figure 1 is a diagrammatic plan view of the cable laying apparatus;

Figure 2 is an enlarged side view of the same at the intermediate point of the cable where the wires are transferred;

Figure 3 is a cross section looking to the left on line 3 of Figure 2 and

Figure 4 is a diagrammatic side view of the apparatus at one end of the cable.

Referring now to the drawings, at each end of the bridge or cable to be laid, this cable being marked A in the drawings, are wire supply reels 10, carrying wires for forming the four strands *a*, and at each end of the bridge or cable a tramway driving mechanism 11, which drive the tramways or traction ropes *b*, *c*, running from opposite ends of the bridge or cable to an intermediate point in the cable where their runs overlap for a short distance. These tramways are arranged in the usual manner to make a continuous run over guide sheaves 12 and driving sheaves 13 at each end of the cable, and over guide sheaves 14 and return sheaves 15

at the intermediate point end of the tramways, all the sheaves being mounted on any suitable supports, from the bridge piers or temporary framework.

6 The wires 1 for forming the strands are carried in loops by the wire carriers, shown as the usual spinning wheels, the frame of which is mounted on and secured to run with tramways *b*, *c*, the spinning wheels *d*, *d'* being on tramway *b* and the others *d*², *d*³ on tramway *c*. The supporting frame of the spinning wheels may be mounted on the tramway in any suitable manner. The wires are shown as passing from the driven supply reel 10 around a fixed sheave 16, a floating tension sheave 17, fixed sheave 18 and guide sheave 19 to and around the spinning wheel and having their dead ends secured to the anchorage in any suitable manner as usual 15 in such constructions. The usual cat-walk or foot-way for the gangs of men working on the cable laying is shown at B.

With this arrangement, as illustrated in the drawings, spinning wheels *d*, *d'* have carried wires from the opposite ends of the cable to an intermediate point of the cable where they have slightly passed each other for transfer of the wire loops, and meanwhile, spinning wheels *d*², *d*³ have carried wires 20 from the intermediate point to the opposite ends of the cable in their return run. The loops on spinning wheels *d*, *d'* will now be transferred between the spinning wheels so that the loop already carried by spinning wheel *d* to the intermediate point of the cable from the right hand end of the cable in Figure 1, will be transferred to spinning wheel *d*², and the loop on *d*² from the left hand end of the cable in Figure 1, will be transferred to spinning wheel *d*. This may readily 25 be done by dropping one loop below the other and then passing the loops across from one spinning wheel to the other. At the opposite ends of the cable, the loops on spinning wheels *d*², *d*³ will be removed and new loops passed over spinning wheels *d*, *d'* for carriage to the intermediate point of the cable. The spinning wheels *d*, *d'* will now move in opposite directions from the intermediate point 30 of the cable to the cable ends, thus completing the run of the respective wires throughout the length of the cable, and the wires on spinning wheels *d*², *d*³ will be carried to the intermediate point of the cable for transfer 35 in the same way as described in connection with the transfer operation of spinning wheels *d*, *d'* and this operation will continue until the strands are completed, when these strands will be bunched in the cable A and 40 four new strands formed by laying up wires as above described.

It will be seen that by this invention, wires are being strung at all times for all four strands, so that, in the same period of time, a loop of wire will be taken across from an-

chorage to anchorage for each of the four strands, instead of for only two strands as in the present method. The gangs of men, also, will have been occupied during the idle half time of the present operation, and all the unreeling mechanisms will be kept in operation, so that the improved method and apparatus not only strings twice the number of wires in a given period of time, but there is no additional expense in equipment except 70 an additional driving mechanism for one tramway and two additional men for transferring the loops of wire at the midway or intermediate point of the cable where the spinning wheels meet. The invention has 75 been illustrated and described in connection with the preferred operation of spinning four strands simultaneously, but it may be applied with advantage to stringing only two strands or more than four strands. 80

It will be understood that the invention is not limited to details of the construction or method illustrated, but that modifications may be made therein without departing from the invention as defined by the claims. 85

What I claim is:

1. The method of spinning cables, which consists in laying cable wires from opposite ends of the cable to an intermediate point of the cable by carriers moving from the opposite ends to said intermediate point and return, then transferring each of the wires at said intermediate point to the other carrier, and completing the lay of the wires through the length of the cable by the return trip of 100 the carriers.

2. In a cable spinning apparatus, the combination of two tramways extending from opposite ends of the cable to an intermediate point of the cable and return, wire carriers 105 driven by said tramways and arranged for the transfer of cable wires from the wire carrier on one tramway to the wire carrier on the other tramway at said intermediate point, for completing the lay of the cable wires through the length of the cable by the return trips of the wire carriers. 110

3. In a cable spinning apparatus, the combination of two tramways extending from opposite ends of the cable to an intermediate point of the cable and return, two wire carriers driven by each of said tramways and moving in opposite directions, said carriers being arranged for the transfer of cable wires from the wire carriers on one tramway 115 to the wire carriers on the other tramway at said intermediate point, for completing the lay of the cable wires through the length of the cable by the return trips of the wire carriers. 120

4. In a cable spinning apparatus, the combination with tramways running from opposite ends of the cable to an intermediate point of the cable and return, of a spinning wheel driven by each tramway and carrying 130

a loop of the cable wire, said tramways and spinning wheels being arranged for the transfer of the cable wire loops from the spinning wheels by which they have been 5 laid to the intermediate point to the spinning wheel running from the opposite end of the cable, for completing the lay of the cable wires by the return trips of the spinning wheels.

10 In testimony whereof, I have hereunto set my hand:

CHARLES C. SUNDERLAND.
